UNITED STATES PATENT OFFICE.

CALVIN LAWYER, OF NEWBURYPORT, MASSACHUSETTS.

TRAFFIC SIGNAL.

Application filed March 26, 1923. Serial No. 627,816.

To all whom it may concern:

Be it known that I, CALVIN LAWYER, a citizen of the United States, residing at Newburyport, in the county of Essex and 5 State of Massachusetts, have invented certain new and useful Improvements in Traffic Signals, of which the following is a specification, reference being had to the accompanying drawings.

10 This invention relates to certain improvements in traffic signals and it is an object of the invention to provide a novel and improved device of this general character adapted to be carried by the vehicle and 15 having novel and improved means whereby notice can be given to the front and to the rear of the direction in which the vehicle is to make a turn or that the vehicle is to stop.

20 It is also an object of the invention to provide a novel and improved device of this general character comprising a semaphore adapted for swinging movement in a vertical direction together with visual 25 means carried by the semaphore to indicate the direction in which a vehicle is to turn or that the vehicle is to stop.

Furthermore it is an object of the invention to provide a novel and improved device 30 of this general character adapted to be supported by the frame of the windshield or other part of the vehicle together with manually operated means for adjusting a semaphore to give the desired signal or indication.

It is also an object of the invention to provide a novel and improved signal of this general character comprising a plurality of separately operated illuminated signals to give the desired indication of warning and wherein the rays from said separate signals are of different colors.

40 The invention consists in the details of construction and in the combination and arrangement of the several parts of my improved traffic signal whereby certain important advantages are attained and the device rendered simpler, less expensive and otherwise more convenient and advantageous for use, as will be hereinafter more fully set forth.

The novel features of my invention will hereinafter be definitely claimed.

55 In order that my invention may be the better understood, I will now proceed to de-

scribe the same with reference to the accompanying drawings, wherein:—

Figure 1 is a view in perspective of a traffic signal constructed in accordance with an embodiment of my invention, a second 60 position of the semaphore being indicated by dotted lines;

Figure 2 is a longitudinal sectional view taken through my improved signal as herein set forth; 65

Figure 3 is a detailed sectional view taken substantially on the line 3—3 of Figure 2.

Figure 4 is an elevational view of the pivoted end portion of the semaphore and opposite to that shown in Figure 1, other 70 positions of the semaphore being indicated by broken lines;

Figure 5 is a diagrammatic view illustrating the circuits for the bulbs arranged within the compartments carried by the 75 semaphore.

As disclosed in the accompanying drawings, 1 denotes a flat member or arm of desired dimension and which is adapted to be clamped or otherwise secured to the frame F of a windshield or other desired part of a vehicle. The inner or securing end portion of the member or arm 1 is provided with a laterally disposed arm 2 for a purpose to be hereinafter more particularly referred to. 80

S denotes a semaphore of requisite dimension and which has one end portion pivotally engaged with a laterally disposed trunnion 3 carried by the outer end portion of the member or arm 1 whereby the semaphore S is capable of swinging movement in a vertical direction. Associated with the trunnion 3 is a nut or head 4 for maintaining the semaphore in operative engagement with the trunnion 3. 90

The nut or head 4 provides a bearing for one end portion of a shaft 5, the opposite end portion of said shaft being disposed through and rotatably supported by the arm 2 hereinbefore referred to. Carried by the shaft 5 inwardly of the arm 2 but in relatively close proximity thereto is a rock arm 6 providing means whereby the shaft 5 may be rocked or rotated in a manner and for a purpose to be hereinafter more particularly referred to. 100

The shaft 5 outwardly of the nut or head 4 has fixed thereto a toothed wheel 7 which engages with the teeth 8 carried by the 110

5 semaphore S. The teeth 8 as herein disclosed are provided by producing suitable recesses in the side face of the semaphore S and said teeth are also concentric to the trunnion 3. By this means upon requisite 10 rocking or turning movement being imparted to the shaft 5, the semaphore S will be raised or lowered as desired.

10 The semaphore S at its outer end portion is provided with a series of transversely spaced compartments 9, herein disclosed as three in number, each of said compartments 9 having their side faces closed by transparent panels 10. Associated with each of 15 the panels 10 is a desired warning or indication 11 such as "Stop," "Left," and "Rite." It is also preferred that the panels 10 carrying the "Stop" indication are red, the panels provided with the "Left" indication being green and the remaining panels 20 10 carrying the "Rite" indication being blue. In addition to warning being given by the indications 11, a further warning is given by the different colored rays as produced by the various panels 10.

25 Carried by the inner end portion of each of the compartments 9 is a socket 12 of a conventional type in which is adapted to be engaged a bulb 14 of an incandescent 30 type. The contact of each of the sockets is connected through the conductor *a* with a source of electrical energy E while a second contact of each of the sockets 12 is electrically connected through a conductor *b*, 35 with a contact member 15 carried by the inner or pivoted end portion of the semaphore S. Carried by the outer end portion 40 of the member or arm 1 is a contact member 16 in electrical connection through the conductor *c* with the source E.

45 When the semaphore S is in its lowermost or normal position, the contact member 16 is free from the contact members 15. When a turn is to be made to the left the semaphore is adjusted, upon proper rocking of the shaft 5, into a position substantially coplanar with the member or arm 1 and when in such position the contact member 16 50 engages the contact member 15 to cause the bulb 14 within the "Left" compartment 9

to burn. When a turn is to be made to the right, the semaphore assumes a position above the horizontal and requisite contact is made by the member 16 to cause the bulb 14 within the "Rite" compartment 9 to 55 burn. When a stop is to be made the semaphore is swung to a position below the horizontal and closes the circuit for the bulb 14 within the "Stop" compartment 9.

60 The outer end portion of the arm 6 is provided with an inwardly and laterally directed lug 6^a which has close contact with the arcuate cross head 2^a whereby the semaphore S is effectively held in its various positions.

65 From the foregoing description it is thought to be obvious that a traffic signal constructed in accordance with my invention is particularly well adapted for use by reason of the convenience and facility with 70 which it may be assembled and operated, and it will also be obvious that my invention is susceptible of some change and modification without departing from the principles and spirit thereof and for this reason I do not 75 wish to be understood as limiting myself to the precise arrangement and formation of the several parts herein shown in carrying out my invention in practice except as hereinafter claimed.

80 I claim:

85 A signal of the class described comprising a supporting member provided with a trunnion and with an outstanding arm, a semaphore having one end portion pivotally engaged with the trunnion, a head engageable with the trunnion for holding the semaphore in applied position, a shaft carried by the head and the outstanding arm of the supporting member, coacting means carried by 90 the shaft and semaphore for swinging said semaphore upon rotation of the shaft, and a rock arm carried by the shaft, said rock arm being provided adjacent to its outer end with a laterally disposed lug in close 95 contact with the arm carried by the supporting member.

96 In testimony whereof I hereunto affix my signature.

CALVIN LAWYER.
